US00D451611B1

(12) **United States Design Patent** (10) Patent No.: **US D451,611 S**
Pontarolo (45) Date of Patent: ** Dec. 4, 2001

(54) **MODULAR ELEMENTS WITH AERATION FOR FLOORS**

(75) Inventor: **Valerio Pontarolo**, Cordovado (IT)

(73) Assignee: **Pontarolo Engineering Srl**, Cordovado (IT)

(**) Term: **14 Years**

(21) Appl. No.: **29/108,755**

(22) Filed: **Aug. 4, 1999**

(51) LOC (7) Cl. **25-99**

(52) U.S. Cl. **D25/119; D25/138**

(58) Field of Search **D25/138, 199; 249/28-32**

(57) **CLAIM**

The ornamental design for a modular elements with aeration for floors, as shown.

DESCRIPTION

FIG. 1 is a topside perspective view of a first embodiment of a modular element with aeration for floors;

FIG. 2 is a front side elevation view thereof;

FIG. 3 is a rear side elevation view thereof;

FIG. 4 is a right side elevation view thereof;

FIG. 5 is a left elevation side view thereof;

FIG. 6 is a top plan view thereof;

FIG. 7 is a bottom plan view thereof.

FIG. 8 is a top side perspective view of a second of a modular element with aeration for floors;

FIG. 9 is a front side elevation view thereof;

FIG. 10 is a rear side elevation view thereof;

FIG. 11 is a right side elevation view thereof;

FIG. 12 is a left side elevation view thereof;

FIG. 13 is a top plan view thereof; and,

FIG. 14 is a bottom plan view thereof.

UNITED STATES PATENT AND TRADEMARK OFFICE
CERTIFICATE OF CORRECTION

PATENT NO. : Des 451,611 S
DATED : December 4, 2001
INVENTOR(S) : Valerio Pontarolo

Page 1 of 9

It is certified that error appears in the above-identified patent and that said Letters Patent is hereby corrected as shown below:

Title page.

The title page, showing the illustrative figure, should be deleted and substitute therefore the attached title page.

Drawings.

The drawing sheets, consisting of Figs. 8-14. should be deleted to be replaced with the drawing sheets, consisting of Figs. 8-14, as shown on the attached page.

Signed and Sealed this

Twenty-eighth Day of May, 2002

Attest:

Attesting Officer

JAMES E. ROGAN
Director of the United States Patent and Trademark Office
